(57) **CLAIM**

The ornamental design for a liquid container, as shown and described.

DESCRIPTION

FIG. 1 is a front perspective view of a liquid container.

FIG. 2 is a front elevation view thereof.

FIG. 3 is a rear elevation view thereof.

FIG. 4 is a side elevation view thereof.

FIG. 5 is an opposite side elevation view thereof.

FIG. 6 is a top plan view thereof.

FIG. 7 is a bottom plan view thereof.

FIG. 8 is a second front perspective view thereof; and,

FIG. 9 is a bottom perspective view thereof.

The broken lines in the drawings illustrate the portions of the design that form no part of the claim.

1 Claim, 9 Drawing Sheets
